United States Patent Office

Des. 192,396
Patented Mar. 13, 1962

192,396

POSTAGE METER BASE

Wally Charles Hoff and Robert Somerville, Toronto,
Ontario, Canada, assignors to The McBee Company
Limited, Toronto, Ontario, Canada

Filed Apr. 24, 1961, Ser. No. 64,860

Term of patent 14 years

(Cl. D64—11)

FIG. 2

FIG. 1 is a perspective view of a postage meter base showing the top surface, one side, and one end, embodying our new design; and

FIG. 2 is another perspective view thereof, showing the top surface and the side and end opposite to those shown in FIG. 1.

We claim:

The ornamental design for a postage meter base, as shown.
